DIRECTION FINDER LOOP AND CONTROL

John A. Prector, Lexington, Mass., assignor, by
mesne assignments, to General Electric Com-
pany, a Corporation of New York

Application May 22, 1928. Serial No. 279,736

9 Claims. (Cl. 250—33.)

This invention relates to radio direction finding and more particularly to an improved rotatable loop structure and associated control mechanisms. Heretofore the loops used in radio direction finders were subject to serious disadvantages in that they were readily disarranged and rendered inoperative by the inclemency of the weather and the destructive action of salt water.

In addition, suitable mounting means adapted to maintain the loop structure in a stable, fixed position permitting rotation of the loop proper in a pre-determined manner, have not been generally available.

It is an object of the present invention to provide an improved loop structure for radio direction finders.

Yet another object of this invention is the provision of an improved mounting means for radio direction finders.

A further object of this invention is the provision of a novel method of making such structures.

These and other desirable objects and advantages will be described in the following specification, and illustrated in the accompanying drawings, it being understood that the form shown is simply a preferred embodiment of the invention, for since the underlying principles may be incorporated in other specific mechanical devices without departing from the spirit and scope of the present invention, it is not intended to be limited to the device shown, except as such limitations are clearly imposed by the appended claims.

In the drawings, like numerals refer to similar parts throughout the several views, of which

Fig. 1 is a front elevation, partly in section, of the loop structure, its casing, pedestal, and supporting tripod;

Fig. 2 is a perspective view of an insulating washer;

Fig. 3 is a perspective view of an insulating bushing;

Fig. 4 is a vertical section of an insulating tube showing an improved method of weaving the loop leads thru the pedestal;

Fig. 5 is a vertical section of a portion of the main housing in the region of the hand hole, drive and collector rings.

Fig. 6 is a detail section on line 6—6 of Fig. 5 and shows the adjusting and positioning means of the drive mechanism;

Fig. 7 is a horizontal section on the line 7—7

of Fig. 5, and shows the collector rings and brush assembly;

Fig. 8 is a front elevation of the brush assembly as viewed from the hand-hole in the main housing;

Fig. 9 is a side elevation partly in section of the main housing for the mechanical compensator and shows the indicator yoke and the leads from the collector rings together with the Sperry repeater support;

Fig. 10 is a plan view taken on line 10—10 of Fig. 9, looking down on the compass and the indicating mechanisms; and

Fig. 11 is a vertical section taken from line 11—11 of Fig. 9, showing the indicator yoke, reading glass and Sperry repeater mechanism.

The loop structure, as shown particularly in Fig. 1, comprises a substantially rectangular frame composed of side tubular members 2 which may be of any suitable conducting material, such as aluminum. These tubular members are fitted into right-angled sockets 3, 4 and 5, forming an apex at two sides of the rectangle and at the bottom are fitted into the Y-connection 6. The angles 3, 4 and 5 are provided on either side with removable metallic plates 7, which provide access to the interior of the connections for a purpose to be described in detail later.

The loop proper consists of a plurality of turns of suitable aerial wire woven thru suitable supports 8 and 9. A plurality of supports 8 is provided for the angular members 3, 4, 5, previously referred to, and are substantially rectangular in shape and provided with a sufficient number of circumferentially arranged holes to accommodate the wires of the loop winding.

Referring to angle member 4, it will be noted that the spacer member 8 is adapted to fit into a plurality of slots 10 and 11 at opposite corners of the angle proper. The cover plate 7, when removed, permits the introduction of member 8 into its appropriate slot, or in event of servicing, permits its ready withdrawal. The spaces in members 3 and 5 are exactly similar to the one just described.

The combination spacer and terminal mounting member 9 is provided in the Y-member 6, the loop ends being designated respectively as 12 and 13 and the mid-point thereof as 14.

By the use of metal throughout a rigid construction is assured, together with ease of removing and mounting. To prevent complete shielding of the loop and therefore complete interception of electro-magnetic waves by the cas-

60

105

110

ing rather than the loop windings, there is provided an insulating bushing 15 and insulating washer 16 between the tubular member 2 and associated angle member 4.

5 Tubular member 2 is provided with a shou-
dered portion 17 upon which the bushing 15 is
adapted to be seated. Interposed between the
end of the tube 2 and inwardly projecting shoul-
der 18 of member 4, is the insulating washer 16
10 above referred to. The bushing and washer may
be of any suitable insulating material, such as
bakelite, hard rubber or other like substances
having the necessary physical and dielectrical
characteristics. By the interposition of these
15 members between the metallic parts of tube 2
and angle 4, the electrical path around the loop
casing is interrupted. The resultant winding
permits magnetic coupling with incoming sig-
nal waves but eliminates any disturbing static
20 coupling due to surrounding objects which would
be the case if the loop casing formed the com-
plete electrical circuit.

A preliminary step in the assembly of the loop
25 is the connection of the various parts, the tubu-
lar members being fitted into the angles and
secured thereto by any suitable means, the cover
plates 7 being removed. The casing is then set
on a suitable jig and the spacer members 8 and
30 9 fitted into their respective slots. The loop
winding 19, usually a continuous length of wire,
is then threaded or woven thru the spacers, care
being taken to maintain the proper spacial ar-
rangement. The resultant winding is a cage-like
35 structure of wires substantially parallel thruout
their entire length. The ends of the loop, as
above noted, are connected to suitable terminal
posts 12 and 13, and the electrical mid-point of
the loop is connected to a tab 14. This tab 14
40 is grounded to the casing at 20 thru a suitable
condenser 21 which is usually of .5 mf capacity.
This structure gives a symmetrical loop, the elec-
trical characteristics of which will be referred
to more in detail later.

The Y-casing 6 comprises the leg portion 22,
45 having an inwardly shouldered portion 23, to
which the mid-point lead of the loop is ground-
ed, and a recessed shoulder 24 into which is fitted
the insulating plate 25' adapted to support the
spacer member 9 and also thru which are thread-
50 ed the loop leads 12' and 13'.

Below portion 23 of the Y-member there is
provided two integral concentric portions 25, 26,
55 which in cross-section present substantially in-
verted U-shaped bearings. The outer member
25 is provided with a plurality of tabs 27 to re-
ceive machine screws 28, which pass thru open-
ings 29 in member 26 and engage openings 30
in the shaft 31.

The lower portion 26 above referred to is
60 provided with a shouldered portion 32 which is
fitted with bushings or bearing rings 33, substan-
tially rectangular in cross section. This bear-
ing member is secured to the ring in any suit-
able manner.

65 The head support 34 has an internal bearing
face 35, between which and bearing face 33 of
the pedestal are interposed suitable bearings
36. Cover rings 37 and 38 are provided at the
top and bottom of the inside of member 34
70 respectively for the purpose of protecting the ball
bearings from moisture.

The member 34 is provided with a plurality of
lugs 39 which are adapted to receive suitable
ends of members 40.

75 The tripod members comprise head-piece 41,

shanks 42 and tail-pieces 43. The head-pieces
are shouldered as at 41' to fit in between mem-
bers 39 and are provided with suitable apertures
to receive the securing members 40. The shanks
are fitted into members 41 in any suitable man-
ner and are held therein by means of studs 44.
The tail-pieces 43 engage suitable supports 45
which are apertured to receive suitable secur-
ing members 46, which may be of any construc-
tion and are provided with base portions 47
adapted to fit the deck or cabin roof and are held
in position thereon in any suitable manner, as
by bolt and nut construction 48, and suitable
washers 49.

80 The construction just described provides a rigid
yet adjustable supporting means for the loop
casing structure, and its pedestal, upon which
said loop structure is adapted to be rotated.

The shaft 31, as above noted, is secured to the
Y-casing by the machine screws 28. At its lower
95 portion, this shaft is threaded at 50 in member
51 and secured thereto by set screws 52. Mem-
ber 51 is secured to rotatable casting 53 by any
suitable means (not shown), the casting 53 being
rotatably mounted on the base casting 54 secured
100 to the deck by bolt and nut construction 55, suit-
able ball bearings being provided between mem-
bers 53 and 54.

For permitting ease of assembly and disas-
sembly, members 51 and 53 may have interposed
105 a diaphragm member (not shown) secured by
bolts 56 which permits rotation of the two mem-
bers, and is adapted to take up any undue
stresses, thus permitting increased flexibility in
operation. Where such a diaphragm is used,
110 suitable material is employed to prevent access
of moisture to the interior of the structure.

The loop leads are carried thru the pedestal
member in the following manner:—The leads
115 are woven thru insulating members 57, made of
cork, bakelite or other suitable insulating ma-
terial, and are thence woven thru insulating tubes
58, provided with apertures 59 at the top
and bottom sides.

120 Interiorly of the tubes 58 the leads are crossed
over at a sufficient angle to minimize capacity
effects, such as would ordinarily be encountered
between parallel disposed conductors. A plu-
rality of these insulating devices and spacing
members 57 is provided in order to prevent
125 grounding contact of the loop leads with the
metal of the conduit. By the use of a number of
these members, reversal of production of the elec-
trical fields around and about the wires is ef-
fected, such reversal being so calculated as to
130 provide substantial neutralization of any capac-
ity effects.

135 Subjacent to the member 54 and positioned
within the cabin or deck house, is the main drive
housing 60, secured to a supporting tubular mem-
ber 61 by a plurality of set screws 62. The mem-
ber 61 is fixedly secured to the member 54 above
referred to and acts as a support for the drive
housing. The drive housing is preferably cast
140 as an integral member having a circular abutting
oprtion 63, the bottom cut-turned apron or
flange portion 64, and an intermediate internal
annular flange 65. There is also provided at one
side of this upper portion a substantially rectan-
145 gular portion comprised between lugs 66 and 67,
on to which is bolted the cover plate 68, the plate
being secured to the legs by suitable machine
screws 69, engaging tapped apertures 70, 71 in
the lugs. The hand-hole thus provided permits
150

the ready inspection of the loop driving mechanism, which will now be described in detail.

Hollow shaft 72, of any suitable conducting material, is secured at its upper portion to the member 53, and is substantially a continuation of the member 31. This shaft 72 is provided with suitable driving mechanism, comprising a collar 73 provided with spiral gear 74, engaging gear 75, the gears being cut at an angle of 45° and the construction being substantially as shown and described in my combination case, Serial No. 29,919, filed March 13, 1925, for Rotating loop aerials.

The present device is distinguished from my prior construction by the inclusion of oiling members 76, 77, 78, bearing against the movable parts of the rotating mechanism and adapted to keep it fully lubricated. Oiling means 76 is positioned in a channel in the drive casing 79 and the oiling means 77 is channelled in the base plate 80, which abuts the member 72, and is secured to member 79 by any suitable means, such as machine screws 81 engaging tapped apertures 82 in the casing 79. The details of the helical gearing and its associated controls have been described in the case above referred to, and such description is not repeated here except as to the details necessary to point out the improvements over such prior structure.

Lubricating device 78 is provided in a ring 83 which is secured to flange 65 of the drive housing, and this ring acts as a support for the ball bearings interposed between said lug and the lower portion of the driving shaft. This lower portion of the driving shaft comprises the collar or tube 84, suitably apertured at 85 and 86 to receive machine screws 87 and 88, which are adapted to secure it to the tube 72. The tube 72 extends nearly to the bottom of the shouldered portion 89, being held therefrom by the screws above described. Member 84 is provided with a plurality of lugs 90, to which is secured the insulating plate 91 by means of a plurality of screws 92. Circumferentially of the insulating plate on top and bottom are placed a pair of opposed collector rings 93, 94, the rings being held in cooperative engagement with the insulating plate by means of machine screws 95, 96, these screws being insulated from opposite plates so that 95 forms an electrical contact or terminal for ring 93 and member 96 forms a like function for ring 94.

The leads from the collector rings are woven thru the insulating member 97 and pass thence upwardly to the members 58, being disposed, as above noted, to avoid capacity effects.

The bottom of member 84 forms an integral cup which is provided with a depending central extension 98. Plate 99 of the compensator described in my above application, fits over this extension and is secured to the shaft by any suitable means, such as machine screws 100. The shaft 101 of the compensator is provided with head plate 102, secured thereto by screws 103 and is associated with the loop drive which has been previously described in the application above referred to.

Referring now particularly to Figs. 7 and 8, there is shown a collector brush assembly comprising a base plate 104, upon which are positioned a pair of insulated mounting posts 105, secured to the base plate by suitable spring washers 106 and nuts 107. At the upper portion of these supporting posts, there is superimposed a spaced insulating plate 108. This plate is tapped

to receive the upper ends of the supporting posts and is secured thereto by a plurality of securing members 106, 107. At its central portion this plate is apertured to receive the adjustable screw fastening means 109, which passes thru the outside of the casing and, cooperating with the lock nuts and washers 110 and 111, is adapted to secure the assembly in position. At the other end of the arcuate base plate 104 there are provided apertures 112 adapted to receive studs 113. These studs are fixed to the bottom of the casing by any suitable means, being threaded on either bottom portions and fixedly secured thereto by the combination locking nuts and washers 114.

The collector brushes 116, 117 are secured to the mounting posts in any suitable fashion, as by means of a plurality of screws 115. These collector brushes comprise a plurality of strips of conducting metal, such as copper, shown more particularly in Fig. 7, the strips being so arranged as to provide maximum constant pressure on the members bearing against collector rings 93, 94. Suitable terminals 118, 119 are connected to the brushes thru the intermediacy of connecting strips 120, 121. Flexible leads 122, 123 are fastened to the terminals in any approved manner, and lead to the radio apparatus positioned in the base receiver of the direction finder.

The casing 63 is provided with an opening to permit the introduction and removal of this brush assembly with a minimum of trouble. An aperture is provided with a cover 124 adapted to be secured to the casing in any suitable manner, as by means of screws 125, a weather-proof gasket such as valenoid or the like 126 being interposed between the cover and the casing. The casing is also provided at either side of the aperture referred to above with inwardly projecting shelf portions 127, upon which are mounted the studs 113 above referred to.

When it is desired to remove the brush assembly for any purpose, whatsoever, it is merely necessary to remove the cover, unscrew the locking member 109, and disconnect the terminal leads 122, 123, after which the base 104 is lifted up and out of engagement with the supporting studs 113, whereupon the entire structure may be withdrawn from its position. It will now be appreciated that such a construction enables the assemblage and mechanical and electrical testing of the brush assembly as a separate unit before it is placed in its appropriate position in the direction finder assembly, and further that this ease of assembly likewise affords a like degree of disassembly. The collector brush assembly has but three points of contact with the fixed casing, and by this simplicity of structure and ease of servicing facilitates the manufacture and maintenance of the direction finder assemblies.

If it is necessary to raise the brush unit in order to insure perfect contact with the respective collector rings, it is merely necessary to insert washers of appropriate thickness between base plate 104 and the locking nuts 114.

In Fig. 9 there is shown the main housing for the compensator 128, which is secured to the main drive casing by suitable means, such as screws 129, the mechanical part of which is substantially shown and described in my above designated application, Serial No. 29,919.

The shaft 101 is prolonged thru the bushing 130 of the compensator housing and is adapted at its lower end 131 to receive the tapped central boss 132 of the indicating yoke 133. This yoke is secured to shaft 101 by means of set screw 150

134. The yoke is substantially U-shaped in cross section, comprising two lateral arms 133, 133', depending from the central supporting boss sections 132. At either end of the arms, the yoke members are provided with slotted portions 135, 136, adapted to receive members 137, 138, which are secured to the yoke by suitable screws 139. Members 137, 138 are prolonged forwardly to provide clamping support means for the rotating glass 140. This glass is provided with a suitable frame 141, coating with the receiver portion 142 into which the lens is adapted to fit. Suitable screws 143 are provided to secure the two parts of the lens holder in cooperative engagement. Member 142 is adapted for rotation about spindles 144 at right angles to members 137, 138. Stop members, such as screws 145, 146, are secured to members 137, 138 immediately behind spindles 144, and are adapted to serve as limiting stops for the lens structure. The lens supporting arms 137, 138 are possessed of several springs and are suitably conformed to provide frictional engagement with the lens support in order that it may be variably adjusted and held in any desired position.

25 The lens supporting construction shown permits the reading of the scale at any position, by merely reversing the lens, thereby obviating the necessity of the operator shifting his position when taking a reading.

30 At the bottom of the arms the yoke is secured to the sighting device 147, which will now be described.

35 This device comprises a glass member having substantially parallel sides at its intermediate portion which is adapted to fit in between the sides of the yoke member. At either side of the yoke the glass member is inwardly constricted and along its middle axis is provided with a plurality of lines. These lines comprise a top line which is normally filled with a black pigment, and a bottom line in the same vertical plane as the black line, the bottom line being filled with a red pigment for the purpose of differentiating it from the upper line. The function of these lines will be described in detail hereinafter.

40 The direction plate is secured to the yoke member in the following manner. The supporting member 148 is secured to the yoke by means of suitable screws 149. Interposed between member 148 and 147 are suitable connection means 150, which may be a gasket of felt or any other suitable material. Centrally of this supporting member there is provided a securing knob 151, which is adapted to receive the screw member 152. This screw passes thru a suitable aperture in the geometric center of the sighting plate and engages the bottom supporting plate 153, which is spaced from the sighting plate by suitable gasket material as above described. By the means just described, the sighting plate is secured to the yoke member and adapted to rotated therewith.

45 In sighting, the operator sights along the black line, taking care that he does not observe any portion of the red line. A showing of any portion of the red line would immediately indicate error in the reading, due to diffraction or parallax. These red and black lines are distinguished from the red and white sense pointers 154, 155, which are integral with the yoke structure and indicate the direction of the incoming signal. These sense indicators are at right angles to the above lines, and are distinguished therefrom by the functions above noted.

50 As shown in Fig. 11, the indicating structure just described is fitted for the receiver casing, and is adapted to co-operate with the dummy compass or a Sperry repeater, indicated generally by 156.

55 In operation, the navigator or radio operator, rotates the loop by means of the hand wheel until a desired maximum signal is received in the radio set associated with the loop. The loop is then rotated until a null point is reached. The null point is used to check up the point or direction of maximum signal reception, due to its relative clearness from interfering signals and other trouble. As is well known, the null point is substantially 90° from the point of maximum signal reception, and serves to determine the aforesaid point with greater definiteness than is possible by trying to measure the strength of signal at either side of the maximum.

60 The point of maximum signal reception and the null point are read off on the scale, the lens being rotated, if necessary, to permit ease of reading.

65 The direction of the signal having been established and noted with respect to the scale setting of the instrument, the corrected reading is transmitted to the navigator to enable him to determine his position and course, as may be necessary.

70 It will now be seen that there has been provided a novel loop structure and loop rotating mechanism, together with a loop indicating device, the whole being adapted to permit the speedy reception of signals while compensating for the electrical and magnetic disturbances set up as a result of the proximity of ship's rigging, hold, electrical machinery, etc., while assuring proper reading of the instrument with a minimized chance of error due to parallax.

75 Having the several turns of the loop symmetrically arranged within its shield preserves the symmetry of electrical capacity to ground, when the loop is tuned and nearer metallic objects.

I claim:

1. In a radio direction finder, the combination with the loop aerial comprising a plurality of concentric turns, of a substantially tubular metallic casing having a plurality of straight sides and itself concentric with and enclosing said loop turns from the weather of the external atmosphere; apertured spacing plates extending inside the metallic enclosing tube across it hollow interior at its corners at substantially forty-five degrees to its sides, said tube supporting said plates, and said loop-wires threading thru the apertures in the spacing plates; said metallic enclosing tube being formed at its corners with apertures extending in both directions from said corners along the sides of the tube and providing access to both sides of said spacing plates; metallic plates covering said tube-apertures and removably secured to the metallic walls of the tube around said apertures; an insulating member thru which said plural loop turns extend, said member being interposed between neighboring alined open ends of the metallic tube and closing the interior of the tube from the weather but opening its electrical circuit; the metallic tube being formed at its bottom with a loop-lead opening; and a vertically disposed hollow metallic rotatable shaft mechanically connected to the metallic enclosing tube in position alined with said bottom opening, the loop leads extending down thru said hollow shaft; said mechanical connec-

- tion between the hollow shaft and enclosing tube sustaining the weight of the entire loop structure above it including the metallic enclosing tube itself and the spacing plates and loop-turns, and 5 causing rotation of said structure as the unitary rotatable element of the direction finder. 80
2. In a radio direction finder, the combination with the loop aerial comprising a plurality of concentric turns, of a tubular metallic casing concentric with and enclosing said loop-turns from the weather of the external atmosphere; means inside said metallic enclosing tube and supporting the loop-turns in insulated relations with the tube; an insulating tube spacing apart two neighboring ends of the metallic enclosing tube and having its hollow interior alined with the hollow interior of said metallic tube, said loop-turns extending thru said insulating tube and the latter forming an electrical opening in the circuit of 10 the concentric enclosing metallic tube but enclosing the interior of the metallic tube and the enclosed loop turns from the weather; means holding said metallic and insulating tubes in said cooperative relations; said enclosing tube including at its bottom a separate hollow open-ended 15 metallic Y-member of which two hollow legs space apart two other neighboring ends of the enclosing tube and communicate with the interior of the insulating tube and the rest of the metallic tube, the wires of the plural loop leads extending thru said two hollow legs of the Y-member; the plural leads from the loop extending out of the metallic enclosing tube by way of the open end of said third hollow leg of the Y-member; and a 20 hollow rotatable shaft vertically disposed and supporting said third hollow leg of the Y-member and mechanically connected thereto for rotation thereof, said third hollow leg itself supporting the entire loop-structure above it as a unitary rotatable element of the direction finder including the metallic and insulating tubes and the enclosed loop-turns, said loop-leads extending down thru said hollow shaft. 25
3. In a radio direction finder the combination with the loop aerial comprising a plurality of concentric turns, of a tubular metallic casing concentric with and enclosing said loop-turns from the weather of the external atmosphere and having at its bottom a hollow downwardly 30 projecting metallic member communicating in both lateral directions with the interior of the rest of the tubular enclosing structure, and forming with the adjacent ends of the tubular structure a Y-shaped metallic construction; two facing alined ends of the tubular structure at a location other than said downwardly projecting member being substantially spaced apart to provide an open circuit structure; a tube of insulating material having its interior alined with the facing interiors of said spaced ends and closing the space against the weather; means holding the metallic and insulating tubes in said cooperative relation; means inside the metallic enclosing tube and insulating the loop-turns therefrom; and a hollow metallic shaft secured to and alined with said downwardly projecting portion for rotation of the entire tubular structure as a unit of the direction-finder. 35
4. In a radio direction finder, the combination with a loop aerial comprising a plurality of concentric turns, of a tubular metallic casing concentric with and enclosing said loop-turns from the weather of the external atmosphere; and means supporting the loop-turns in insulated relations with said metallic enclosing tube; the 40 bottom of the hollow metallic enclosing tube including a hollow open-ended downwardly projecting metallic portion thru which extend the leads of said loop aerial; the metallic enclosing tube having two neighboring spaced but facing ends at a location other than said hollow open-ended metallic projecting portion; an insulating member apertured for passage of said loop-turns and holding said neighboring ends of the metallic enclosing tube in spaced-apart insulated relations to one another, said insulating member enclosing the space between the ends of the metallic enclosing tube and cooperating with it in enclosing the plural loop-turns from the weather; and a hollow metallic rotatable shaft supporting said hollow metallic projecting portion, alined therewith for downward passage of the loop-leads, and mechanically connected with said metallic projecting portion for rotation of the metallic enclosing tube, said metallic projecting portion supporting the entire loop-structure above it as a unitary rotatable element of the direction finder including the metallic enclosing tube and the apertured insulating member. 45
5. In a radio direction finder, the combination with the loop aerial comprising a plurality of concentric turns, of a tubular metallic casing concentric with and enclosing said loop-turns from the weather of the external atmosphere; means inside said metallic enclosing tube and insulating the loop-turns from said tube; the bottom of the casing being provided with a hollow open-ended metallic Y-member of which two hollow legs are mechanically connected with two neighboring ends of the tubular metallic casing alined with said two legs of the Y-member, the loop-leads extending thru said two legs and out of the loop-turn enclosing structure by way of the open-ended third leg of the Y-member; the metallic enclosing tube having two neighboring alined and facing but spaced-apart ends at a portion exposed from said metallic Y-member; and an insulating member apertured for passage of said loop-turns and holding said neighboring ends of the metallic tube in their said spaced-apart relation and in insulated relations to one another, said insulating member enclosing the space between the spaced-apart ends of the metallic tubes and cooperating with the latter in enclosing the plural loop - turns from the weather; and a hollow rotatable shaft vertically disposed and supporting said third hollow leg of the Y-member and mechanically connected thereto for rotation thereof, said third hollow leg itself supporting the entire loop-structure above it as a unitary rotatable element of the direction finder including the metallic tube and apertured insulating member and the enclosed loop-turns, said loop leads extending down thru said hollow shaft. 50
6. In a radio direction finder, the combination with the loop aerial comprising a plurality of concentric turns, of a tubular metallic casing concentric with and enclosing said loop-turns from the weather of the external atmosphere, and having at its bottom a hollow downwardly projecting metallic member communicating in both lateral directions with the interior of the rest of the tubular enclosing structure and forming with the adjacent ends of the tubular structure a Y-shaped metallic construction; a spacing and insulating member interposed between neighboring alined ends of the tubular metallic structure at a location other than said downwardly pro- 55

jecting member at which location the insulating member open circuits the electrical circuit of the tubular enclosing structure, said insulating member being apertured for the passage of the loop-wires but closing the space between said neighboring ends of the metallic tubular structure and cooperating with the latter in enclosing the loop-turns from the weather; means insulating the metallic enclosing tube from the loop-turns; and 10 a hollow rotatable metallic shaft vertically disposed and mechanically connected to said hollow downwardly projecting metallic member and aligned with the hollow interior of the latter, said mechanical connection sustaining the weight of 15 the entire loop-structure as a unitary rotatable element of the direction finder.

7. In a radio direction finder, a loop, terminal leads for the loop, a housing enclosing the terminals, and a guide for the leads within the 20 housing said leads being retained in substan-

tially symmetrical and intersecting relationship.

8. In a radio direction finder, a loop, leads from the loop, and means to mount the leads in substantially fixed relation to the loop, said means including insulating tubes apertured at both ends to provide lead-in apertures for the leads, and said leads passing through said tubes diagonally of the apertures and of each other. 80

9. In a radio direction finder, a loop, leads from the mid-point and ends of the loop, a tubular pedestal, a condenser mounted on the pedestal and connected to the mid-point lead, a separate tubular member of insulating material within the pedestal, said tubular member having lateral opposed apertures at its ends, said loop end leads passing through one pair of said opposed apertures and reversely through said other pair of opposed apertures, thus forming means for suspending said tubular member. 85 90
